UNITED STATES PATENT OFFICE.

THOMAS H. KNOLLIN, OF SYRACUSE, NEW YORK.

KEY-PEDAL FOR PIANO-FORTES.

SPECIFICATION forming part of Letters Patent No. 225,289, dated March 9, 1880.

Application filed November 17, 1879.

To all whom it may concern:

Be it known that I, THOMAS H. KNOLLIN, of Syracuse, in the county of Onondaga, in the State of New York, have invented new and 5 useful Improvements in Attaching Church-Organ Pedals to a Piano, of which the following, taken in connection with the accompanying drawings, is a full, clear, and exact description.

10 This invention relates to a novel application of church-organ pedals to the keys of a piano, designed more especially for practice of the use of such pedals.

15 The following will enable others skilled in the art to make and use my invention.

In the accompanying drawings, Figure 1 is a front elevation of a portion of a piano provided with my invention; Fig. 2, a vertical transverse section of same; and Fig. 3 is a side 20 view of the pedal-frame and roller-board detached.

Similar letters of reference indicate corresponding parts.

P represents a piano of any ordinary style 25 and construction, and having the keys A A pivoted in the usual manner. B B denote 30 pedals similar to those used on a church-organ, and pivoted at their rear end in the usual frame, C, surrounding the pedals. The forward 35 end of the frame C is provided with standards D, which embrace the outer side of the side rails, E, of the so-called "roller-board" F, and are detachably connected therewith by pins a and a' passing through the same.

40 The roller-board I place in front of the lyre, which carries the pedals of the piano, and arrange it with its top inclined toward the front of the piano, thereby allowing the bottom portion of the roller-board and the pedals to be 45 placed farther under the piano and brought nearer into the same relative position as those of a church-organ. The roller-board is detachably connected to the piano by pins e e passing through pendent plates or arms G on 50 the under side of the piano-case, and through the upper extremity of the side rails of the roller-board.

By the described peculiar connection of the roller-board with the pedal-frame C and 55 the piano the pedal-frame can be removed without disturbing the roller-board, or, when

desired, both can be removed bodily; and by removing one of the lower connecting-pins, a', and using the other as a pivot, the roller-board can be laid down upon the pedal-frame, as indicated by dotted lines in Fig. 3 of the drawings, and thus the apparatus folded into a compact and convenient compass for storing or transportation.

r r' are the rollers pivoted horizontally on 60 the roller-board F, and provided, respectively, with arms s and s', through one of which passes the end of a pendent rod, u, having adjusting-nuts n and interposed washers or cushions w at opposite sides of said arm. The lower end 65 of the rod u passes through a horizontal plate, b, connected to the lower end of the side rails, E, of the roller-board. Below the plate b the rod u is provided with two collars or shoulders, d and d', a sufficient distance apart to 70 admit between them the end of the pedal B, which bears on the lower collar, d. This collar is connected with the plate b by a rubber band, f, hooked onto pins on the said collar and plate, respectively. By means of the band 75 f the rod u is yieldingly forced upward, and limited in this movement by the collision of the upper collar, d', with the under side of the plate b.

To the arm s' is connected a rod, v, which 80 is extended upward through a guide-bar, l, attached to the roller-board, and terminated with a right-angled bend or hook, o, near the under side of the piano-case. The hook o engages the eye of a link or rod, t, which passes 85 through the bottom of the piano-case, and is at its upper end hooked into a staple, t', pendent from the forward end of the key A, as best seen in Fig. 2 of the drawings. The intermediate link, t, however, may be dispensed 90 with, and the staple t' extended through the piano-case bottom, and provided at its lower extremity with an eye for the reception of the hook o.

The described form of the hook o allows the 95 same to readily enter and withdraw from its connection with the staple or link t automatically with the attachment and removal of the roller-board.

H represents the so-called "pedal-check," de- 100 signed to support the pedals, and prevent their action on the keys when the use of the former

- desired. This pedal-check consists of a right-angled triangular bar arranged transversely underneath the pedals, and hinged at its right angle to the bottom of the cross-piece I of the pedal-frame, and having a space, *k*, between their adjacent sides. To the under side of the respective pedals is attached a pin or lug, *g*, directly over the space *k*, and of a size to enable it to enter the same. The pedal-check is provided with an upward-projecting arm or lever, *h*, by means of which it can be tilted, so as to cause its top edge to bear against the cross-piece I, and thus close the space *k*. When weight is then applied to the pedals their action is arrested by the lug *g* coming in contact with the top edge of the pedal-check. The pressure coming outside of the hinge-joint of same tends to retain it in its tilted position.
- It will be observed that by the described peculiar construction and arrangement of the pedal-check hinged to the bottom of the pedal-frame, with the space *k* at its side and the support of the pedals directly over the said space, the extra extension in the height of the pedal-frame and the corresponding elevation of the piano are obviated.
- Having thus described my improvements, what I claim as new, and desire to secure by Letters Patent, is—
1. The roller-board F, arranged in front of the lyre L, and with its top inclined toward the front of the piano, substantially in the manner described and shown.

2. The combination of the pedal-frame C, 35 having standards D, the roller-board F, connected thereto by the removable pivoted pin *a* and pin *a'*, and to the plates G by the removable pins *e e*, substantially as described and shown.

3. The combination of the key A, provided near its forward extremity with the staple *t'*, the rod or link *t*, hooked into said staple and passing through the piano-case bottom, and the rod *v*, detachably connected with the link 45 *t*, substantially as described and shown.

4. In combination with the removable roller-board E and link *t*, the rod *v*, having at its upper end the right-angled bend or hook *o*, substantially as described and shown.

5. The right-angled triangular pedal-check H, hinged at its right angle to the bottom of the pedal-frame C, and having the space *k* between its hinged edge and the cross-piece I, in combination with the pedals B, provided 55 with the lug or pin *g*, substantially in the manner and for the purpose specified and shown.

In testimony whereof I have hereunto signed my name and affixed my seal, in the presence of two attesting witnesses, at Syracuse, in the 60 county of Onondaga, and State of New York, this 12th day of November, 1879.

THOMAS H. KNOLLIN. [L. S.]
